COVERED EXPANSION JOINT

Richard T. Lyons, Toronto, Ontario, Canada, assignor to The Patent and Licensing Corporation, New York, N. Y., a corporation of Massachusetts

Application December 18, 1948, Serial No. 66,014

3 Claims. (Cl. 72—106)

1

This invention relates to a device for covering the vertical faces of expansion joints in masonry constructions. This invention is primarily concerned with a device for covering the vertical faces of expansion joints containing heat-liquefiable rubberized bituminous sealing compositions.

In the construction of large concrete structures, such as buildings, dams, swimming pools and the like, the concrete portions of the structures are formed in sections and joints between adjacent sections are provided to accommodate the expansion and contraction of the concrete under the atmospheric conditions encountered in service. These joints are filled with an adhesive, elastic sealing compound, rubberized bituminous compositions which may be liquefied at elevated temperatures of the order of 400° to 500° F., and poured into the joint being particularly suitable for this purpose. A problem arises, however, in connection with the vertical face of expansion joints in which such sealing compositions are employed. When the liquefied sealing material is poured into the joint there is a tendency for it to run out along the vertical face of the joint before the material has had time to solidify. Further, sealing compositions employed for this purpose exhibit cold flow and, during periods of expansion when the space between adjacent concrete sections is narrowed, the sealing material tends to be forced out of the vertical face of the joint and becomes displaced, making the joint unsightly and sometimes causing permanent injury to the bond between the composition and the concrete.

It is an object of the invention to provide a device which will afford lateral support for the sealing composition in vertical faces of expansion joints.

It is a further object of the invention to provide a device of the character indicated which will be suitable for permanent installation across the vertical face of an expansion joint and which will prevent objectionable displacement of the sealing composition during periods of expansion.

According to the invention, I provide an expansion joint covering assembly comprising a pair of guide elements adapted to be secured to the masonry units adjacent each side of the vertical face of the expansion joint, and a joint covering member adapted to be positioned between the guide elements and to be partially embedded in the expansion joint sealing composition.

Other objects and features of my invention will be apparent from the following description and from the accompanying drawing in which,

Fig. 1 is a sectional view taken along the line 1—1 of Fig. 2, and,

2

Fig. 2 is a view in perspective showing the vertical face of an expansion joint provided with a joint covering assembly embodying my invention.

Fig. 3 is a front elevation of a concrete structure showing the vertical face of the expansion joint covered by a plurality of my joint covering assembly.

Referring to the drawing, the numeral 10 designates generally the guide elements forming part 10 of my expansion joint covering assembly. Each guide element 10 comprises an elongated flat base 12, a shoulder 14 extending outwardly from the base 12 along a lateral edge thereof and terminating in a forwardly extending flat flange 16. The plane of the flange 16 is substantially parallel to the plane of the base 12 but is offset therefrom by reason of the shoulder 14. The base 12 is provided with spaced openings for the reception of fastening means for securing the guide elements 20 to the masonry surface adjacent the expansion joint. It will be observed that each guide element is substantially Z-shaped in cross-section.

The joint covering member of my assembly is T-shaped in cross-section and comprises an elongated body 18 and perpendicular web 20 extending outwardly therefrom. Preferably, the web 20 is provided with a series of perforations 22.

In practice, my expansion joint assembly is positioned across the vertical face of the joint before the joint sealing composition is poured. Firstly, 30 the guide elements 10 are secured to the surface of the masonry adjacent the joint and parallel to the sides thereof, the flat base 12 being placed against the masonry. In the embodiment illustrated the guide elements 10 are so positioned that the outer edge of the flat flange 16 is flush with the side of the joint. The elements 10 may be secured by any suitable means. A satisfactory securing means is shown in Fig. 1, comprising a nail 24 driven into an expansion element which is inserted into a recess in the masonry. The expansion element is formed by two flared semi-cylindrical liners 25 held together by a flexible metal clamp 26. When the nail 24 is driven the liners 25 are forced against the sides of the recess 35 whereby tight frictional engagement with the nail 24 is effected. After the guide elements 10 are in place, the body 18 of the joint covering member is slipped downwardly into the channel between the face of the masonry and the inner faces of the flat flanges 16, with the vertical web 20 extending into the joint. The joint sealing composition 27 may then be poured into the joint. If desired, the body 18 may first be directed into position across

50 the face of the joint and the guide elements 10 55 then secured to the masonry surface.

The guide elements 10 and the joint covering member are conveniently formed of black iron of say 10 to 15 gauge and may be of any desired length, depending on the joint to be covered. I have found one to five feet a convenient length for my joint covering assembly for use under conditions normally encountered in pouring joint sealing compositions with known pouring equipment. Thus, when used in conjunction with a long joint e. g. the joint between sections of a dam, I prefer to use a series of short assemblies placed one above the other as shown in Fig. 3, rather than a single long assembly.

It will be apparent that various changes and modifications may be made without departing from the invention as defined in the appended claims and it is intended, therefore, that all matter contained in the foregoing description and in the drawing shall be interpreted as illustrative and not in a limiting sense.

I claim:

1. A structure comprising vertically-disposed masonry structural units having laterally adjacent vertical surfaces, an expansion joint between said structural units having a vertical face disposed between the vertical surfaces of said units, a resilient flowable expansion joint sealing composition in said joint, elongated guide elements of substantially Z-shaped cross-section removably secured along one surface thereof to the said vertical surfaces of the masonry units adjacent the said expansion joint and substantially parallel to the sides of the said vertical face of said joint, whereby to form an elongated channel between the vertical surfaces of the said structural units and the surfaces of said guide elements parallel thereto, and a covering unit for the vertical face of the expansion joint comprising a substantially flat elongated body portion positioned within said channel across the vertical face of the expansion joint and a perpendicular longitudinal web extending into and embedded in said sealing composition, said body portion having a thickness less than the depth of said channel whereby to permit limited outward movement of the said body portion from the vertical face of the joint during periods of expansion of the masonry units and lateral movement of said sealing composition out of the vertical face of said joint but preventing displacement of said sealing composition from said joint.

2. A structure comprising vertically disposed masonry structural units having laterally adjacent vertical surfaces, an expansion joint between said structural units having a vertical face disposed between the vertical surfaces of said units, a resilient, flowable expansion joint sealing composition in said joint, elongated guide elements of substantially Z-shaped cross-section removably secured along one surface thereof to the said vertical surfaces of the masonry units adjacent the said expansion joint and substantially parallel to the sides of the said vertical face of said joint, whereby to form an elongated channel between the vertical surfaces of the said structural units and the surfaces of said guide elements parallel thereto, and a covering unit for

the vertical face of the expansion joint comprising a substantially flat elongated body portion positioned within said channel across the vertical face of the expansion joint and an apertured perpendicular longitudinal web extending into and embedded in said sealing composition with portions of the sealing composition extending through the apertures in the web, said body portion having a thickness less than the depth of said channel whereby to permit limited outward movement of the said body portion from the vertical face of the joint during periods of expansion of the masonry units and lateral movement of said sealing composition out of the vertical face of said joint but preventing displacement of said sealing composition from said joint.

3. A structure comprising vertically disposed masonry structural units having laterally adjacent vertical surfaces, an expansion joint between said structural units having a vertical face disposed between the vertical surfaces of said units, a resilient, flowable expansion joint sealing composition in said joint, a plurality of elongated guide elements of substantially Z-shaped cross-section removably secured along one surface thereof to the said vertical surfaces of the masonry units in vertically-superposed relationship adjacent the said expansion joint and substantially parallel to the sides of the said vertical face of said joint, whereby to form an elongated channel between the vertical surfaces of the said structural units and the surfaces of said guide elements parallel thereto, and a plurality of vertically superposed covering units for the vertical face of the expansion joint, each of said covering units comprising a substantially flat elongated body portion positioned within said channel across the vertical face of the expansion joint and a perpendicular longitudinal web extending into and embedded in said sealing composition, said body portion having a thickness less than the depth of said channel whereby to permit limited outward movement of the said body portion from the vertical face of the joint during periods of expansion of the masonry units and lateral movement of said sealing composition out of the vertical face of said joint but preventing displacement of said sealing composition from said joint.
